UNITED STATES PATENT OFFICE.

PEARL Y. SMILEY, OF KITCHENER, ONTARIO, CANADA.

BOOT.

Application filed October 5, 1922. Serial No. 592,613.

To all whom it may concern:

Be it known that I, PEARL Y. SMILEY, of the city of Kitchener, Province of Ontario, Dominion of Canada, a subject of the King of Great Britain, have invented certain new and useful Improvements in Boots; and I do hereby declare that the following is a full, clear, and exact description thereof.

For full comprehension, however, of my invention, reference must be had to the accompanying drawings in which similar reference characters indicate the same parts, and wherein:

Figure 1 is a perspective view of a boot constructed according to my invention;

Figure 2 is a sectional view taken on line 2—2 Figure 1;

Figure 3 is a detail fragmentary sectional view of the lacing flies, and

Figure 4 is a sectional view taken on line 4—4 Figure 1.

My invention relates particularly to waterproof high boots. Heretofore in the manufacture of footwear of this type it has been necessary to provide a comparatively large opening adjacent the ankle portion to permit the withdrawal of the last and consequently it has been extremely difficult to obtain a snug fit around the wearer's ankle. The looseness in some instances has been taken up by folding the surplusage, but this is objectionable for the reason that continued folding cracks the material causing leakage and the folds render the wearing of the boot uncomfortable.

The object of the present invention is to provide a boot of this type which will conform to and snugly fit the ankle without necessitating the folding hereinbefore mentioned and in which the possibility of leakage is practically eliminated.

Another object of importance is to provide a boot the foot or shoe portion of which will be of a very flexible and light weight construction. Such a construction not only adds to the wearer's comfort but secures a sure footedness in climbing over rough, stony and slippery places not obtainable with the usual boot and also enables the boot to be almost turned inside out enabling the lining to be thoroughly dried.

A further object of the invention is to provide a boot having a neat appearance and which can be manufactured at a comparatively low cost.

The embodiment illustrated consists of a

foot or shoe portion 2 and a leg or stocking portion 3, the latter extending to the knee or the thigh as desired and having its lower end united to the foot portion at a point 60 below the ankle.

The foot portion is adapted to be built on a low close fitting last and has the flexibility of the ordinary running shoe. It consists of a fabric lining 4, lasted to an insole 5 65 and extending to a point just below the ankle, a gum or rubber covered vamp 6 having the same flexibility as the leg portion; quarters 7 which are superimposed upon the lower end of the leg portion; counter 8 70 slightly stiffer than the vamp but nevertheless very flexible; sole 9 of a weight similar to that employed in connection with overshoes or galoches; a comparatively light heel 10 which owing to its flexibility enables 75 the associated parts to be of light weight construction; and a foxing 11.

The stocking or leg portion 3 as hereinbefore mentioned is also very flexible and elastic and consists of a fabric lining 12 80 having an outer covering of rubber 13, the weave of the lining being such that it permits the inherent elasticity of the rubber to be fully utilized. The stocking is constructed of two vertical sections united at the 85 front and back thereof by lap seams 14, the seams reinforcing the stocking and enabling it to be uniformly folded when not in use. This leg portion adjacent its lower end has a restricted ankle portion 15 which is adapted to conform to and snugly fit the ankle without the necessity of the folding which has been practised with boots of somewhat similar types heretofore in use. The leg portion extends down over the instep and 90 below the ankle and overlaps and is secured to the lining 4 by an endless joint closed by a rubber bead 16, the joint being substantially horizontal viewing the boot in side elevation and extending from the vamp back 95 to the heel. In order to add to the appearance of the shoe the endless bead 16 may be of any color which will contrast favorably with the remainder of the boot.

The quarters 7 which are superimposed 105 upon the lower end of the stocking portion are constructed from a unitary strip of very narrow width adjacent the heel as indicated at 17 and which widens out over the instep and terminates on opposite sides there- 110 of in lacing flies 18. These flies are free from and adapted to overlie the leg por-

tion and are provided with eyelets 19 to enable them to be laced together by a lace 20. To eliminate the possibility of leakage at the point at which each fly joins the stocking each fly is provided with an attachment strip 21 which is secured to the stocking and which extends towards the other fly, the whole being further reinforced by an oval patch 22 which is positioned upon the instep and slightly overlaps the attachment portion.

Owing to the fact that the boot is built up on a low close fitting last a very small opening is required to permit the withdrawal of the latter and consequently a restricted ankle portion is provided which will conform to and snugly fit the wearer's ankle. This form fit and the inherent elasticity of the boot prevents it from slipping up and down on the wearer's foot as is usually experienced. The lacing flies assist in obtaining a firm grip upon the foot, and the soft pliant construction of the boot in general gives it all the properties of a moccasin.

What I claim is as follows:

1. A boot of rubberized material comprising a foot portion located entirely below the ankle consisting of a lining, vamp, counter, and sole and an elastic leg portion extending down over the instep and ankle and attached to the foot portion, said leg portion having a restricted opening at the ankle adapted to snugly fit the same without distortion of its cross-section.
2. A boot of rubberized material comprising a foot portion located entirely below the ankle consisting of a lining, vamp,

counter and sole and an elastic leg portion extending down over the instep and ankle and attached to the foot portion, said leg portion having a restricted opening at the ankle and adapted to snugly fit the same without distortion of its cross-section, and quarters located entirely below the ankle and superimposed upon the leg portion and connected to the foot portion and terminating in lacing flies.

3. A boot of rubberized material comprising a foot portion located entirely below the ankle consisting of a lining, vamp, counter, and sole and an elastic leg portion extending down over the instep and ankle and attached to the foot portion, said leg portion having a restricted opening at the ankle and adapted to snugly fit the same without distortion of its cross-section, and quarters superimposed upon the leg portion and connected to the foot portion and terminating in lacing flies, each of said flies having attachment portions extending laterally in opposite directions relatively thereto and adapted to be attached to the leg portion, and means reinforcing the leg portion at the instep and between the flies, said means consisting of a layer of rubberized material positioned upon the instep portion and overlapping the adjacent attachment portions of the flies.

In testimony whereof I have signed my name to this specification in the presence of two witnesses.

PEARL Y. SMILEY.
